UNITED STATES PATENT OFFICE.

WILLIAM FETTER, OF BALTIMORE, MARYLAND.

SELF-HEALING TUBE.

Application filed July 16, 1923. Serial No. 651,804.

To all whom it may concern:

Be it known that I, WILLIAM FETTER, a citizen of the United States of America, residing in the city of Baltimore, State of Maryland, have invented certain new and useful Improvements in Self-Healing Tubes, of which the following is a specification.

The invention relates to a self-healing inner tube for pneumatic tires of the type in which puncture-healing plastic is enclosed within a pocket in the tread portion or zone of the tube, the plastic serving to heal the puncture by entering the opening found in the tube wall and hardening therein, either forming a plug or cementing the edges of the wound together, or both.

The present invention has particular reference to a new arrangement of the pocket or pockets in the tread or outer puncturable walls of the tube.

In accordance with the invention, the pockets are formed on both sides of the tube wall, i. e., on the inside and on the outside thereof, the tube wall being made of three thicknesses of rubber for this purpose; each pocket is of relatively small area and the pockets on the opposite sides overlap so that the entire puncturable area is covered with pockets containing puncture-healing material.

In the preferred form, as shown, these pockets are circular in plan and those on each respective side of the tube wall are placed close together, the circles being substantially tangent to each other and the spaces between the circular pockets on one side are covered by the pockets on the other side of the tube wall, the pockets on one side being concentric with the spaces between the pockets on the other side.

In the accompanying drawing, I have shown an inner tube for a pneumatic tire, embodying my invention in the preferred form.

48 In the drawing:

Figure 1 is a transverse section through the tube.

Figure 2 is a side view of a fragment of the tube.

50 Figure 3 is a fragmentary section on the line 3, 3 of Figure 1, the inside of the tube beyond the plane of the section also being illustrated.

Referring to the drawing by numerals:—
55 The tube as shown has its tread walls formed

of three layers of vulcanized rubber, 1, 2 and 3.

The outer layer, 1, of rubber is vulcanized or otherwise made integral with the middle portion, 2, certain areas being left 60 free to form circular pockets, 4, placed close together, each pocket except on the edges of the puncture-healing portion being substantially in contact with four other neighboring pockets on the same side of the tube 65 wall. These pockets are filled with puncture-healing material, 5.

Between the center portion, 2, and the inner portion, 3, I show similar pockets similarly spaced but each pocket, 6, on the 70 inside overlies and is concentric with a space, 7, between four outer pockets, 5, so that the entire area of the tube wall containing the pockets is protected.

The device of the invention has important advantages, including the fact that when badly punctured at any point, the entire content is not ejected as may happen with the ordinary double wall tubes, the protection over most of the area 80 is double and there is no tendency, as in the tubes having large pockets, of one wall of the pocket to slide or become displaced relatively to the other.

I have thus described specifically and in 85 detail a single tube or self-healing tube embodying my invention in order that the nature and operation of the same may be clearly understood. However, the specific terms herein are used descriptively rather 90 than in a limiting sense, the scope of the invention being defined in the claims.

What I claim and desire to secure by Letters Patent is:

1. An inner tube for pneumatic tires having the tread zone thereof provided with small pockets, some on the inner side of the tube wall and others on the outer surface of the same, self-healing material filling the pockets, the pockets on each side of 100 the wall being so placed that they overlap, the pockets thus overlapped extending over the entire tread area of the tube.

2. An inner tube for pneumatic tires, the tread wall of said tube being formed of 105 three sheets of flexible material, superimposed one on the other, a series of small pockets between the outer sheet and the middle one, and a series of pockets formed between the middle sheet of material and 110

2
the inner sheet, the pockets in one series
overlying and covering the spaces between
the pockets of the other series and so that
the combined pockets of the two series ex-
5 tend over the entire tread area, and a quan-
tity of puncture-healing material in each
of said pockets.

Signed by me at Baltimore, Maryland,
this eleventh day of July, 1923.

WILLIAM FETTER.
